VERTICALLY ADJUSTABLE TABLES FOR
FOURDRINIER MACHINES

Lawrence L. Lapeyrouse, Mobile, Ala.

Application June 10, 1932, Serial No. 616,528

2 Claims. (Cl. 92—44)

This invention relates to machines for the making of paper and particularly to machines used in making caliper or fourdrinier board, that is, relatively thick paper board, this present invention being an improvement of the structure shown in Figure 2 of my Patent No. 1,853,625 granted to me on April 12, 1932. My prior patent described and showed a number of different forms of fourdrinier machines in which means were shown whereby the making wire was run on an incline for a certain distance from the breast roll and over the sieve table and was then carried rearward for the remaining part of the distance either in a horizontal plane, an upwardly inclined plane or at a declination. The purpose of this construction was to provide means whereby the stock water could be "rushed" up over the inclined portion of the wire but at a point where the head pressure was spent, the wire was caused to travel either on a less inclination or in a horizontal plane or on a downwardly and rearwardly inclined plane to thus prevent the stock water from "dragging", this construction permitting a board to be made which would have a high bursting strength and but little weight.

The present invention provides means whereby the rear section of the table, formed of two sections as disclosed in my prior patent, may be raised at both ends or either end, thus making it possible to raise one end of the second section of the table more than the other if desired and to make it possible to get any angle of the two sections of the table that it is required to get. A further object is to provide a construction which may be readily used for converting machines now in use to include the principles of the invention which are disclosed in my prior patent.

40 My invention is illustrated in the accompanying drawing, wherein:—

Figure 1 is a diagrammatic side elevation of a fourdrinier machine constructed in accordance with my invention;

45 Figure 2 is a fragmentary elevation partly in section showing the manner in which the front section is mounted upon the supporting arm.

In the drawing, there is illustrated diagrammatically a fourdrinier in which is provided the usual breast roll 10, the couch roll 11, the guide roll 12, the tube rolls 13, the wire rolls 14 and the suction boxes 15. The web or sheet of wire netting 16 passes around the rolls 10 and 11 and over the rolls 12 and 13 and over and under the rolls 14 in the usual manner. One of the rolls

14 is provided with means whereby the slack in the wire netting or web may be taken up. The frame 17 which supports the rolls 13 is formed in two sections hinged to each other at 18 so that the forward section extending from the hinge 18 to the breast roll is relatively short and the rearward section extending from the hinge 18 to the couch roll 12 is relatively long. This frame 17 is carried upon the support 19. This support is mounted adjacent its opposite ends upon jack screws 20 operating in the screw-threaded bases or sockets 21.

The screws 20 may be swiveled to the support 19 and be caused to rotate to vertically adjust the support or the bases 21 may be rotatable to cause the raising or lowering of the screws 20.

As before stated, the frame 17 is formed in two sections 17 and 17^a. The section 17^a is connected at its forward end to a support 22 which is attached to the stand 23 for the breast roll 10.

The particular improvement which I have illustrated consists in the use of the two screw jacks 20 disposed beneath the forward and rear ends of the support 19 which support supports the long or main section of the frame 17. It will be obvious that by raising the forward end of the support 19, an increased angle will be given to the section 17^a of the wire supporting frame and thus to the forward portion of the wire and that by adjusting the rear screw 20, the rear section of the frame 17 with the rear portion of the wire, that is, all that portion of the wire rearward of the hinge 18 may be adjusted so that the rear section of the table may be disposed at a less inclination than the forward section 17^a, may be disposed in a horizontal plane, or may decline rearward and downward. Thus it is possible to get any angle of the two sections of the table desired and at the same time secure all the advantages which are present in the structure shown in my prior patent.

It is to be particularly noted that in my construction the suction boxes 15 are disposed at the rear portion of the frame 17. This is particularly important as it is necessary that the paper or board formed on this machine acquire bulk and a better formation on the short section 17^a and the drag be controlled on the long section 17 before the paper reaches the suction boxes. This is particularly important because when the sheet reaches the suction boxes, it is set and the formation cannot be changed. The formation of a sheet of paper is effected and altered by the flow of the stock water and this formation of the sheet must be accomplished while there is still enough

water left to float the fibre. The suction boxes act to remove the water from the sheet when there is not enough water left to flow and the water must be drawn out.

5 In the structure shown in Figure 2 of my prior patent, the forward section or portion of the wire could be inclined upward and rearward but necessarily with that construction the second section or rearward section had to be extended 10 downward and rearward.

With my present construction, however, the rear section of the wire may be kept in a horizontal plane without regard to the adjustment of the forward section or it may be disposed at any 15 desired angle to the forward section. This structure is particularly cheap to manufacture and I have found that it makes it possible to convert the ordinary fourdrinier machine into an adjustable fourdrinier machine as disclosed in my prior 20 patent.

It will be seen that I have provided a sieve table which is inclined at a relatively steep angle for a certain distance from the breast roll but in which the rear portion of the table may be horizontal, inclined upward and rearward at a lesser 25 angle to the forward section of the table or declined, thus enabling the stock water to be "rushed" up the wire for a part of the distance over the sieve table and then on a less incline or 30 on a level or on a slight decline over the remainder of the table, thereby preventing the stock water from dragging on the latter part of its journey over the sieve table. By my construction, I can secure a relatively great inclination 35 of that part of the sieve table adjacent the breast roll without having any dragging effect.

It is to be noted that in my structure, the hinge 18 is disposed about one-third the distance from the breast roll to the suction boxes so that the 40 forward section 17a is very much shorter than the rear section 17. The forward section 17a is upwardly inclined. On this section, water is forced to rush up this incline due to the head pressure in the stock box. The water, therefore, 45 travels faster over the upwardly inclined section than does the wire 16. At the point 18, the greater part of the water has passed through the wire, very little water remaining in the layer of pulp on the wire. There is no force or pressure, therefore, at this point. The small amount of water 50 which is left in the stock is now pulled by the wire 16 which acts in the manner of an undertow or current. The making wire 16 as it passes over the section 17 travels faster than the surface water, that is, than the small amount of water 55 in the stock and this water tends to drag or lag through its inertia. If a good deal of water was retained in the sheet, any downward inclination of the rear section 17 of the table would 60 cause the water to rush downward instead of acting as a drag but there is not enough water to rush downward and, therefore, the water remaining in the sheet acts as a drag. The purpose of the adjustable rear section 17, therefore, 65 is to control the extent of this drag. A level rear

section does not entirely eliminate excessive drag. It is, therefore, ordinarily necessary to incline the rear section downward just sufficiently to prevent excessive drag and the degree of inclination must be carefully adjusted. Heretofore it was necessary to change the hydration of the stock in order to prevent this dragging of the water on the rear section but to add more water would change the desired qualities of the finished product but by inclining the rear section downward to just the proper amount, any excessive dragging is eliminated without changing the hydration of the stock. The amount of drag depends upon the different stocks being handled, some requiring a great deal of dragging, others only a very slight drag. Precisely the amount of drag desired can be secured by properly adjusting the section 17 and it will be seen that by raising the forward end of the section 17, the forward section 17a may be inclined at any desired angle and that the rear section then may be brought, by adjusting the rear end thereof, either into a horizontal plane, an upwardly inclined plane or a downwardly inclined plane.

I claim:

1. In a fourdrinier machine, a breast roll, a couch roll, a wire extending from the breast roll and couch roll, a sieve table, the sieve table being formed in two sections, the forward section adjacent the breast roll being shorter than the rear section and being pivoted to the rear section at a point between the suction boxes and the breast roll and having table rolls, means for vertically adjusting the forward end of the rear section to thus adjust the inclination of the forward section of the sieve table, and independent means for vertically adjusting the rear end of the rear section of the sieve table relative to the forward end thereof, the rear section carrying suction boxes at its rear portion, and wire supporting rollers from the suction boxes to the point of connection with the forward section.

2. In a fourdrinier machine, a breast roll and a couch roll, a wire extending around the breast roll and couch roll, a frame extending longitudinally beneath the upper flight of the wire and formed in two sections, the forward section being short relative to the rear section and the forward section extending rearward from the breast roll and being pivoted to the rear section, wire supporting rolls carried by the two sections of the frame, suction boxes disposed in connection with the rear end of the rear section of the frame, means operatively connecting the forward end of the forward section to the breast roll, a support extending longitudinally beneath the rear section of the frame and supporting the same, means for vertically adjusting the forward end of said support to thus adjust the inclination of the forward portion of the frame, and independent means for vertically adjusting the rear end of the support to thus adjust the angle of the rear section to the angle of the forward section of the frame.

LAWRENCE L. LAPEYROUSE.
